FACE MASK

Benjamin Cooper, Woodmere, N. Y.

Application January 12, 1955, Serial No. 33,935

Term of patent 14 years

(Cl. D34—2)

FIG. 1.

FIG. 2.

Fig. 1 is a front view of a face mask showing my new design, and

Fig. 2 is a side elevation of the same.

The broken lines shown in Fig. 2 of the drawing indicate the elastic mask string which is applied to the mask at its sides at a level approximating the eye of the wearer for mounting the mask on the head of the wearer.

I claim:

The ornamental design for a face mask, as shown and described.
